UNITED STATES PATENT OFFICE.

EMIL TYDEN, OF HASTINGS, MICHIGAN.

SEAL-LOCK.

No. 874,712.

Specification of Letters Patent.

Patented Dec. 24, 1907.

Application filed June 11, 1906. Serial No. 321,092.

To all whom it may concern:

Be it known that I, EMIL TYDEN, a citizen of the United States, residing at Hastings, in the county of Barry and State of Michigan, have invented new and useful Improvements in Seal-Locks, of which the following is a specification, reference being had to the accompanying drawings, forming a part thereof.

This invention relates to a class of locks adapted to be used for securing the closures—doors or covers—of boxes, cabinets, cars and apartments so that a rupturable seal may be applied which shall be removable only by rupture, and which will necessarily be ruptured in the forcible opening of the closure-door or cover.

It consists in the features of construction shown, described and set out in the claims.

In the drawings:—Figure 1 is a plan view of a portion of the lid of a box secured by a lock embodying the invention. Fig. 2 is a section at the line 2—2 on Fig. 1. Fig. 3 is a section at the line 3—3 on Fig. 1. Fig. 4 is a view similar to Fig. 3 so far as the lock is concerned, the cover being removed and the locking bolt being shown in position for opening the closure. Fig. 5 is a detail section at the line 5—5 on Fig. 3 showing the bolt turned for disengaging the catch nose to permit the cover to be lifted. Fig. 6 is a plan view of portion of a box having the lid secured by a seal lock embodying a modification of the invention shown in the preceding figures. Fig. 7 is a section at the line 7—7 on Fig. 6. Fig. 8 is a section at the line 8—8 on Fig. 7. Fig. 9 is a view similar to Fig. 7 showing the parts in position for receiving the seal, the lid being closed but securing the bolt at unlocked position.

40 In the drawings, 1 represents one side wall of the box, cabinet or apartment to be secured by a cover or door represented at 2. The lock whose case or bolt-supporting element, 3, is shown secured to the wall, 1, comprises in addition to said case, 3, a bolt 4, and a spring, 5.

6 is a plate secured to the door or cover, 2, having an aperture, 6^a, through which the head of the bolt passes when the door or cover is closed. The head of the bolt which thus extends through the aperture, 6^a, is an L-shaped hook, 4^a, whose reversed terminal, 4^b, is adapted to pass through a hole, 7^a, in the rupturable seal, 7, and thence to extend back through the aperture, 6^a, in the plate, 6, for retaining the seal when the bolt is in

locked position. The bolt head has also a sloping-faced tooth, 4^c, having an abrupt shoulder or face toward the plate, 6, and seal, 7, and adapted to overhang the margin 6^c of the aperture, 6^a, of the plate and 7^a, of the seal, and thus to engage the cover or door, 2, to prevent its accidental opening when no seal is present, and also to relieve the seal of the rupturing strain which would result from 65 any movement tending to open the door if it were not thus engaged by the said tooth. The outer face of the tooth, 4^c, is sloped for encounter with the under edge of the aperture, 6^a, of the plate or of the corresponding aperture in the cover when the latter is closed. The spring, 5, is a flat piece of steel secured at one end to the case and having the other end bearing laterally against the side of the bolt, and the bolt is 75 cut away at one side forming an abrupt shoulder, 4^d, and a plate bearing surface, 4^e, for the spring. The position of the cut-away surface, 4^e, of the shoulder, 4^d, with respect to the hook head, 4^a, of the bolt is such 80 that the bolt head is in position shown in Fig. 1 adapted to register with and enter the aperture, 6^a, of the plate, 6, when the spring is lodged on the face, 4^c, and above the shoulder, 4^d, of the bolt. In this position the device 85 operates as a simple spring catch.

The tooth, 4^c, of the bolt head being encountered by the margin of the aperture, 6^a, as the cover is closed, and the bolt being deflected by such encounter sufficiently to permit the tooth to pass through the aperture, the pressure of the flat spring, 5, against the flat face, 4^c, of the bolt exerting an elastic pressure upon the bolt, tends to resist the turning movement and retract the bolt back 95 through the angle through which it is turned while the tooth is passing through the aperture, and by such retraction brings the tooth back into position for engagement outside the plate overhanging the margin of the aperture. In this position the terminal, 4^b, of the bolt, as stated, extends back through the aperture, 6^a. When a seal is to be applied the bolt will be turned quarter way around to the position shown in Fig. 4 and then withdrawn lengthwise until stopped by the cross-pin, 4^f, which is set through its lower end and stops against the lower end of the case or bearing frame, 3. In this position the end of the spring, 5, bears against the cylindrical surface of the bolt below the shoulder, 4^d, and the bolt being now turned back into

normal position, as shown in dotted line in Fig. 4, the cover may be closed, the head of the bolt registering with the aperture, 6^a, and passing through it, and a seal, 7, being 5 laid on the upper side of the plate with its aperture, 7^a, in position under the end of the terminal, 4^b, the bolt may be thrust inward, the terminal passing through the aperture of the seal, and the spring snapping above the 10 shoulder, 4^d, preventing the longitudinal withdrawal of the bolt and thus securing the seal. The seal, by its extent over the plate, 6, across the aperture, 6^a, and by the fact that the aperture, 7^a, is not large enough to 15 permit the tooth, 4^c, of the bolt head to pass through it, prevents the opening of the cover, even when the bolt is sprung aside to disengage the tooth, 4^c, from the plate, because to pass through the aperture the tooth would 20 have to tear away the portion of the seal around the aperture, 7^a, thereof which overlies the aperture, 6^a, under the abrupt shoulder of the tooth. Such rupture of the seal would disclose the fact that the cover had 25 been forcibly opened. In order that the seal may be readily ruptured by one authorized to do so, a slit, 7^b, extends from the aperture, 7^a, nearly to the edge of the seal, so that it is readily ruptured at the end of the 30 slit. The seals are preferably made of thin sheet metal, as tin, or they may be made of card of suitably tough texture. For the purpose of securing the bolt at the position shown in dotted line in Fig. 4, that is, the 35 position at which the cover may be shut down to engage with it before applying the seal and leaving it in position to receive the seal, the bolt has a notch, 4^e, on the side opposite the flat seat, 4^e, and shoulder, 4^d, and 40 this notch is adapted for engagement with the edge of the upper bearing of the bolt at 2^b, and is forced into such engagement by the spring acting at the opposite side when the bolt is withdrawn to the position shown in 45 dotted line in Fig. 4.

In Figs. 6 to 9 inclusive, there is shown a modified form of lock embodying the same invention as defined by certain characteristic features. In this form, the case of the lock 50 may be made from two pieces,—the piece, 11, of sheet metal struck up in a die to form a box, and having formed upon it, protruding inwardly with respect to the box cavity, bosses, 12^a and 12, upon which, respectively, 55 are mounted within the case the two elements of the lock consisting of the bolt, 13, and the dog, 14. The other piece of the case, 15, is a plate, which may have corresponding bosses, 16, of which one is seen in Fig. 8, 60 struck up on the face which is to be the inner face when the two parts of the case are secured together, so that the two pieces meet head to head, and they may serve as the means of securing the two pieces of the case 65 together by short bolts or screws, 18, 18,

which will be completely inclosed within the recesses or cavities formed by striking up the bosses. The two plates of the case may also be secured by the bolts which secure it to the inner side of the box taking through the 70 flanges, 19, 19, of the first-mentioned part and through the corresponding margins of the plate, 15. A lug, 21, is struck up from the plate, 15, opposite the lower end of the dog, 14, and the dog has a centering boss, 75 14^a, facing the lug, 21, for lodgment of a coil spring, 22, which shall react between the tail of the dog and the lug, 21, tending to force the head, 14^b, of the dog toward the proximate edge of the bolt, 13, which is provided 80 with a recess or notch, 13^a, for engagement of the nose of the dog and a sloping projection forming the under side of said notch and the approach thereto, so that when the bolt is pushed from the elevated position shown in 85 Fig. 9, the dog, whose nose, 13^a, is held against the edge of the bolt by the spring, is crowded back over the sloping approach and is thrust by the reaction of the spring into the notch or recess, 13^a, for securing the bolt at 90 locking position shown in Fig. 7. The head of the bolt which protrudes from the case is in the form of a hook, 17, of which the end, 17^a, projects back in the direction of the 95 length of the bolt for engaging the seal as hereinafter explained. This hook head is adapted to enter the bolt aperture, 6^a, of the bolt-receiving plate or hasp plate, 6, which is mounted upon the outer side of the cover or otherwise suitably secured thereto. At 100 the edge of the bolt opposite that from which the hook, 17, projects, it has preferably a sloping nose, 17^b, which is encountered by the margin of the bolt aperture, 6^a, as the plate, 6, is closed down over the bolt; and in 105 such encounter with the upper sloping edge of the nose, 17^b, the bolt is forced edgewise against the pressure of the spring-pressed dog, 14, to permit the plate to pass over the nose, the spring-pressed dog forcing the bolt 110 back to normal position at which the nose, 17^b, overhangs the margin of the bolt aperture and engages the plate, 6, for preventing the accidental disengagement and opening of the cover. The case element, 11, has an aperture, 11^a, in position to permit the finger of the operator to be inserted back of the tail of the dog, 14, for pressing the dog against the tension of the spring to disengage its nose, 115 14^b, from the aperture, 13^a, of the bolt, so 120 that the bolt may be drawn longitudinally a distance which is permitted by the length of the slot, 13^b, of the bolt, by which the bolt is engaged with the boss, 12^a, of the case. The dog being released from the pressure of the 125 finger as soon as the bolt is started away from its locked position, the reaction of the spring against the dog and through it against the bolt causes the notch, 13^b, in the edge of the bolt opposite the dog to become engaged 130

with the edge wall, 11^a, of the case at the end margin of the bolt aperture, 11^b, therethrough, and the bolt is thus retained at withdrawn position until released by the operator.

It will be observed that the lock above described operates as an automatic catch for holding the cover of a box or a hasp which may fasten such cover, and that it is adapted to be released at will for opening the box. The special purpose for which certain features are provided, however, is to adapt the lock to coöperate with a rupturable seal to prevent the box from being opened, except in such manner as to rupture the seal unless the latter has been first independently ruptured and removed. For this purpose, I employ a seal, 20, which is a disk, preferably, of thin sheet metal, having an aperture, 20^a, of suitable size to be entered by the terminal, 17^a, of the hook, 17, of the bolt. A slot or rift is made from the aperture, 20^a, of the seal nearly to the margin; so that it may be easily ruptured at the end of the rift at the margin. The seal is applied by withdrawing the bolt, as above described, until the notch, 13^b, becomes engaged with the edge of the case. At this position the end of the terminal, 17^a, of the bolt hook is above the upper surface of the plate, 6, and the seal disk may be passed under it and up onto the terminal, 17^a, which will enter the aperture, 20^a. The bolt being now disengaged at the notch, 13^b, from the case and pushed inward, will be locked to the dog, 14; and the case being within the box and the aperture, 11^a, being inaccessible, there is no means for disengaging the bolt from the dog to permit the bolt to be drawn upward again for releasing the seal, and any attempt to open the cover forcibly will rupture the seal if persisted in sufficiently to open the cover.

It will be obvious that this seal lock may be applied and operated in the manner described in any position or situation in which the door, cover or closure of any sort which is retained by the bolt prevents access to the aperture, 11^a, of the case through which alone the dog can be reached for disengaging the bolt, and I do not limit myself to any particular situation or character of device, whether box, cabinet or other enclosed room or receptacle.

I claim:

1. A seal lock comprising a bolt which is mounted for two movements, one longitudinal and the other transverse to the longitudinal movement; an element which is adapted to be engaged by the bolt in said transverse movement for securing a closure said bolt having means for engaging such element; a rupturable seal lodged in position obstructing movement of said elements for opening the closure, the bolt having means engaging the seal by longitudinal movement of the bolt

inward for retaining the seal in such obstructing position, and automatic means engaging the bolt to retain it at such seal-retaining position.

2. A seal lock comprising a bolt which has two movements, one longitudinal and the other transverse thereto said bolt being provided with means for engaging a closure; a closure which is engaged in said transverse movement of the bolt and a rupturable seal lodged outside the closure and obstructing the opening movement of the latter, the bolt having means for engaging the seal by longitudinal movement of the bolt inward and automatic means engaging and retaining the bolt at the limit of such inward movement.

3. In a seal lock comprising a bolt which is mounted for two movements, one longitudinal and the other transverse to the longitudinal movement, an element which is adapted to be engaged by the bolt in said transverse movement for securing a closure said bolt having means for engaging such element; a spring which reacts to cause such movement; a rupturable seal lodged in position obstructing the movement of said element for opening the closure, the bolt having means for engaging the seal by longitudinal movement of the bolt inward for retaining the seal in such obstructing position, said spring being adapted for engaging the bolt to retain it at seal-retaining position.

4. A seal lock comprising a bolt which has two movements, one longitudinal and the other transverse thereto said bolt being provided with means for engaging a closure; a closure which is engaged in the transverse movement of the bolt; a spring which reacts to cause such movement; a rupturable seal lodged outside the closure and obstructing the movement of the latter, the bolt having means for engaging the seal by longitudinal movement of the bolt inward, and being adapted also for engagement by the spring for retention thereby at the limit of such inward movement.

5. A seal lock comprising a bolt which is mounted for two movements, one longitudinal and the other transverse thereto; a plate which is apertured to permit the bolt to be thrust through it, the bolt having a projection which engages the margin of the aperture by the transverse movement of the bolt after it is thus thrust through the plate to secure the plate against movement relative to the bolt; a rupturable seal lodged in position obstructing such movement of the plate, the bolt having means engaging the seal by inward longitudinal movement of the bolt and adapted by such engagement to retain the seal in said obstructing position, and automatic means engaging the bolt to retain it at such seal-retaining position.

6. A seal lock comprising a bolt which has two movements, one longitudinal and the

other transverse thereto; a plate which is to be locked by the bolt, having an aperture through which the bolt is thrust in the movement of the plate to position at which it is to be secured by the bolt, the bolt having a projection which engages the margin of the aperture of the plate by the transverse movement of the bolt after it is thus thrust through the plate; a rupturable seal lodged outside the plate and obstructing the opening movement of the latter, the bolt having means for engaging the seal by longitudinal movement of the

bolt inward after its said transverse movement for engaging the plate by the projection, and automatic means engaging and retaining the bolt at the limit of such inward movement.

In testimony whereof, I have hereunto set my hand at Hastings, Michigan, this 5th day of June, A. D., 1906.

EMIL TYDEN.
